UNITED STATES PATENT OFFICE.

GEORGE DONALDSON, OF LEICESTER, ENGLAND, ASSIGNOR TO UNITED SHOE MACHINERY COMPANY, OF PATERSON, NEW JERSEY, A CORPORATION OF NEW JERSEY.

DIE.

1,129,079.

Specification of Letters Patent.

Patented Feb. 23, 1915.

Application filed May 7, 1913. Serial No. 766,176.

To all whom it may concern:

Be it known that I, GEORGE DONALDSON, a subject of the King of England, residing at Leicester, Leicestershire, England, have 5 invented certain Improvements in Dies, of which the following description, in connection with the accompanying drawings, is a specification, like reference characters on the drawings indicating like parts in the several 10 figures.

This invention relates to cutting dies of the type employed in presses for dieing out blanks of sheet material such as leather or 15 leather board for use in soles, heels, or other parts of boots and shoes.

More particularly the invention relates to cutting dies of that type in which interior 20 blades are employed for sub-dividing or cutting the blanks fashioned by the outer portions of the die.

In using dies of this type as heretofore constructed it has been necessary before 25 each dieing out operation to remove from the die the previously cut blank. If this is not done, and the several blanks cut out from the stock are not individually removed from the die, they become wedged or 30 jammed within the die and interfere with its subsequent effective use. The jamming of 35 the blanks within the die is partly the result of the expanding action of the interior blades which, on account of their increasing thickness above the cutting edge, have had a tendency to wedge the died-out material 40 outwardly against the inner surface of the outer walls or that portion of the die employed for cutting the outline of the blank.

An object of the present invention is to 45 improve dies of this general type and render them capable of being used for cutting a continuous series of blanks without the necessity of removing each blank before the next is cut. Thus the use of the die will be rendered more efficient through the reduction 50 of the time required for each of its consecutive operations.

With this object in view an important feature of the invention consists in the provision of a cutting die having interior blades 55 disposed with their cutting edges above or within the plane of the cutting edges of the exterior blades. In using such a die the outline of the blank will be cut before the blank is operated upon by the cutting edges of the 60 interior blades. Subsequently, when the die

is used for cutting the succeeding blanks from the sheet material, the blank already cut will be forced by the newly cut blanks upon the interior blades by which it will be sub-divided or otherwise cut in a configuration determined by the arrangement of the 65 inner blades.

The distance of the cutting edges of the interior blades from the plane of the cutting edges of the exterior blades may be such 70 that the successive operations of cutting the outline of a blank will cause the immediately preceding blank to be acted upon by the interior blades, or it may be so arranged that several blanks are cut to outline before a 75 blank is operated upon by the interior blades.

As herein shown the inner surface of the exterior blades is arranged to diverge outwardly from or near the plane of the cutting edge so that the blanks, as they are cut and passed upwardly through the die by the 80 subsequent operations, will move freely and sufficient clearance will be afforded for the expansion of the blanks caused by the action of the interior blades. It has been found advantageous in some cases to arrange the surface of the interior blades also to diverge similarly to the surface of the exterior blades, or to a lesser extent, so that as 85 the blanks are cut by the interior blades the portions inclosed by them will not be restrained from free movement upwardly within the die.

These and other features of the invention 90 will be best understood and appreciated from the following description of a preferred embodiment thereof selected for purposes of illustration and shown in the accompanying drawings in which;

Figure 1 is a view in perspective of an inverted die for cutting interlocking heel lifts; and Fig. 2 is a vertical section through the center of the die.

The blanks to be cut by the die herein 100 shown are in the form of two U's, inverted in relation to one another, with one arm of each U-shaped blank disposed in the space between the arms of the other. Such blanks as these are used in the manufacture of 105 pieced heels and similar blanks are sometimes used for making rands.

As shown in Fig. 1 the die has external 110 blades 2 with a cutting edge 4 corresponding in outline with the contour of the inter-

locked U-shaped blanks and having its inner surface diverging outwardly from its cutting edge. The die herein shown is provided with a heavy strengthening rib adjacent to its cutting edge, although this feature is immaterial to the present invention. The die is provided with interior blades 8 and 12 which, as herein shown, may be formed of a single bar or plate shaped to cut the intersecting lines of the two U-shaped blanks.

The interior blades are made integral with or otherwise rigidly secured within the external blades 2 and have their cutting edges 10 disposed in a plane above the plane of the cutting edge 4 of the exterior blades. The center member 12 of the interior blades is vertical, that is, at right angles to the plane of the cutting edge, while the other portions 15 8 have their inner surfaces diverging in the same direction but to a lesser extent than the inner surfaces of the exterior blades. This allows for the increasing thickness of the central vertical portion 12 above its cutting 20 edge. The upper edge of the outer portion of the die is thickened in a rib 3 to provide an extended pressure receiving surface and this edge and also the pressure receiving edges of the interior blades are ground to 25 lie in a single plane so that the cutting pressure will be received evenly and transmitted uniformly to every point of the cutting edges.

By the use of a die like that herein described, a continuous series of interlocking heel blanks can be cut without removal from the die, each blank being preliminarily cut to its external configuration and then when the die forms the succeeding blanks, being cut 40 into its two sub-divisions by the interior blades.

While the interior blades herein shown extend from one side of the die to the other and so actually produce two separate blanks, 45 it is within the scope of the invention to employ interior blades which operate to cut only slits within the body of a previously severed blank or to perform some other secondary operation thereon.

Having thus described my invention I claim as new and desire to secure by Letters Patent of the United States:—

1. A die for operating on sheet material, having an exterior blade with a cutting edge 50 shaped to form the outline of a blank, and

an interior blade for performing a secondary operation on a previously severed blank having its cutting edge disposed in a plane above the plane of the cutting edge of the exterior blade.

2. A die for cutting sheet material, having an exterior blade with a cutting edge shaped to form the outline of a blank, the sides of said blade diverging above the cutting edge, and an interior blade disposed 65 with its cutting edge above the plane of the cutting edge of the exterior blade.

3. A die for cutting sheet material, having an interior blade disposed at right angles to the cutting edge of the die, and supplementary cutting blades which diverge 70 above their cutting edges from said interior blade.

4. A die for operating on sheet material, having an exterior portion sharpened to 75 form the outline of the blank, and an interior blade extending continuously from one side of the die to the other and having a cutting edge disposed above the cutting edge of the exterior portion.

5. A die for cutting interlocked U-shaped blanks, having an outer portion sharpened to form the outline of the combined blanks, and an interior blade having its cutting blade disposed in a plane above the edge of 85 the outer portions and shaped to cut the interior lines of the interlocked blanks.

6. A die having a continuous outer cutting edge for forming the outline of a blank, a central blade disposed at right angles to the 90 plane of said cutting edge, and similar connecting blades extending between the ends of the central blade and the outer cutting portion of the die and diverging above their cutting edge from said central blade.

7. A die having a continuous outer portion with a cutting edge located in a single plane, and an interior portion with a cutting edge located above said plane, whereby a blank severed at one time by the outer portion may be subsequently operated upon by 100 the interior portion.

In testimony whereof I have signed my name to this specification in the presence of two subscribing witnesses.

GEORGE DONALDSON.
